UNITED STATES PATENT OFFICE.

LEMMET L. AMSPACKER, OF GLASCO, KANSAS.

WAGON END-GATE.

1,093,963.

Specification of Letters Patent. Patented Apr. 21, 1914.

Application filed May 2, 1913. Serial No. 765,160.

To all whom it may concern:

Be it known that I, LEMMET L. AMSPACKER, a citizen of the United States, residing at Glasco, in the county of Cloud and State of Kansas, have invented a new and useful Wagon End-Gate, of which the following is a specification.

This invention relates to improvements in end gates for vehicles and more particularly to an end gate comprising two sections, either one of which may be removed independent of the other.

An object of the present invention is to provide an end gate comprising two independent sections either one of which may be removed independent of the other and which when rigidly secured in position is practically liquid tight.

A further object is to provide an end gate comprising two independent sections and to form the lower one thereof of two parts hingedly secured together, whereby the lower end gate may be withdrawn longitudinally from the wagon body without disturbing the upper end gate and to furthermore so form the upper end gate that it will when in position tend to hold the side boards of the wagon body in proper spaced relation.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferable form of my invention is illustrated, in which:—

Figure 1 is a rear view in elevation of my improved end gate as secured to a wagon body. Fig. 2 is a top view thereof with portions thereof removed. Fig. 3 is a vertical cross sectional view more clearly illustrating the toggle joint latch.

Referring to the drawings in which similar reference numerals designate corresponding parts throughout the several views, 1 is a vehicle body of any improved construction and includes the upstanding side boards 2, between which side boards extend the upper and lower end gates 3 and

4 respectively. The lower end gate 4 is formed of the two portions 5 and 6 hingedly secured together as at 7, the said hinge extending transversely of the end gate near the center thereof and when the said end gate is in position as illustrated in Fig. 1, the hinge 7 will lie substantially vertical, from which it will be apparent that as the hinge 7 is rigidly secured to the back face of the two portions or sections, the end gate may fold with the central portion extending outwardly to thereby draw the extreme ends of the sections 5 and 6 together with the result that they will become disengaged from the spaced guide members 8 which are rigidly secured to the side boards 2 and extend transversely thereof. The extreme ends of the sections of the lower end gate are rounded as at 9 so that the same may enter between the spaced guide members 8 and may have forced contact with the side boards 2 to thereby insure a practically liquid-tight joint therewith. In order to limit the inward movement of the two sections 5 and 6 about the hinge 7, the locking plate 10 is rigidly secured to the end gate 4 and projects therebeyond to thereby overlap the section 6 which section is provided with a latch 11 adapted to rotate about the shaft 12 which threadedly engages a suitable nut 13 which is embedded in the said section. The locking plate 10 is provided at the overlapping end 14 with a slot 15 which is adapted to pass over the latch member 11 when the same is in one position and is adapted to be engaged by the said latch member when it is rotated from the said position through substantially 90 degrees, the latter position being illustrated in Fig. 1 of the drawings. From the foregoing it will be apparent that the locking plate by contacting with one section and being rigidly secured to the other section of the lower end gate prevents the excessive inward movement of the two sections about the hinge 7 which would bring an undue strain thereon and furthermore the locking plate when engaged by the latch member prevents any relative movement of the two sections of the lower end gate.

The upper end gate 3 is formed of one continuous piece to the extreme edges of which and extending transversely thereacross are the metallic plates 16 which are provided with the outwardly struck lips 17 which are adapted to serve as guides during

the inserting of the upper end gate and which is further adapted to provide means whereby the side boards of the vehicle body may be held in spaced relation when the said end gate is in its final seated position.

Rigidly secured to and extending transversely of the side boards 2 and positioned above and in alinement with the guide members 8 are the metallic guide plates 18, the 10 extreme edges 19 of which are bent inward to form retaining flanges. As clearly illustrated in Fig. 2 of the drawings, the upper end gate 3 is adapted to contact against the inner of the guide plate flanges. In order 15 to hold the said end gate rigidly in position, a strip 20 is provided with a number of threaded apertures extending therethrough and threadedly engaging the same are the wing bolts 21, the same extending through 20 the wagon side boards, through the metallic guide plates 18, and engaging the said strip to thereby bring the same into forced contact with the outstanding lip 17 of the metallic plate 16. The width of the strip 20 25 allows the same to extend between the inwardly extending flanges 19 and to contact at its other edge with the metallic plate 16 and to exert a slight wedging action thereon, it being noted that as illustrated in Fig. 30 2 of the drawings, the said strip is arranged at a slight angle with respect to the guide plate 18. Each of the wagon side boards are provided with the said guide plates and wing bolts as described and thereby are 35 adapted to engage the upper end gate 3 and to hold the same in a rigid manner and also prevent spreading of the side boards of the wagon such as would occur if an excessive pressure is brought to bear thereon. When 40 it is desired to remove the end gate 3 the wing bolts 21 are loosened and the end gate may be then moved upwardly and to thereby draw the lip 17 from between the strip 20 and guide plate 18 which is otherwise held 45 therebetween.

The end gate 3 may be forced down against the lower end gate and is held rigidly in that position. The toggle joint latch member 22 is provided and comprises 50 a base plate 23 rigidly secured to the upper gate 3 and extending across the upper edge thereof. The base plate 23 is provided with the outstanding bifurcated lug 24 rigidly secured to which is the curved latch 25. 55 Pivotedly secured to the curved latch 25 is the U-shaped member 26 the curved portion of which is provided with the threaded aperture 27 extending therethrough to which is threadedly secured the bolt 28. 60 Rigidly secured to the bottom of the vehicle is the hooked member 29 which is detachably engaged by the link 30 extending therebetween and secured to the bolt 28, it being noted that the lower extremity of the link 65 30 is provided with a suitable eye 31 which

is adapted to fit over and engage the hooked member 29 substantially as illustrated.

From the foregoing it will be apparent that the tension exerted by the toggle joint latch member may be varied by turning the 70 bolt 28 and therefore the pressure which will be exerted upon the upper end gate 3 forcing the same into contact with the upper extremity of the lower end gate, which will in turn exert a pressure between the lower 75 portion of the lower end gate and the wagon base, which may be varied according to whether liquid-tight joints between the end gates and wagon body is or is not desired. As illustrated in Fig. 3, the bolt 28 and the 80 link 30 are adapted to contact with the locking plate 10 of the lower end gate and to exert a suitable inward pressure thereon which will thereby tend to relieve the tensile stress from the latch 11.

From the foregoing it will be apparent that the upper end gate may be removed by first disengaging the toggle joint latch member and then loosening the wing bolts 21. The upper end gate may then be drawn 85 upwardly and out of disengagement with the guide members and strip 20. When the two end gates are locked in position, the lower gate may be removed without disturbing the upper end gate by first disengaging the toggle joint latch member to thereby remove the link 30 and bolt 28 from in front of the locking plate 10. The latch 11 is then rotated about its axis until it comes into alinement with the slot 15 which allows the said 90 locking plate to move outwardly and the two hingedly secured sections 5 and 6 of the lower end gate to collapse which will draw their extreme ends inward and disengage the same from the spaced guide members 8. It is to be noted that when the lower 95 end gate is in position it will exert a slight stress upon the side boards, tending to push the same outwardly and which is taken up by the upper end gate, to thereby provide a 100 liquid-tight joint between the side boards and the end gate should it be so desired. The toggle joint may be adjusted as described to exert a varying pressure upon the end gate forcing the same against the bottom of the wagon body and hold the end gate securely in position.

The many advantages of a construction such as I have described will be clearly apparent, among which may be mentioned the mutual independence of the two end gates and the fact that there are no rods and bolts with nuts thereon to be removed every time the end gates are to be detached from the wagon.

Having thus fully described the invention what I claim to be new and original with me is:—

1. Holding means for a wagon end gate comprising plates rigidly secured to the side 130

edges of the end gate and provided with outwardly struck lips, guide plates rigidly secured to the side boards of the vehicle and provided with inwardly bent retaining flanges, strips fitting between the end gate plates contacting with the retaining flanges of the guide plates, and means extending through the vehicle side walls engaging the said strips and adapted to force the same into wedged contact with the guide plate retaining flanges to thereby force the said end gate into forced contact with the remote retaining flange of the guide plates, to thereby draw the vehicle side boards into forced contact with the end gate.

2. The combination with a vehicle body with side boards, of an end gate with metallic plates rigidly secured to the ends thereof, said metallic plates provided with outstanding lips, metallic guide plates rigidly secured to the body side boards and provided with inwardly extending side flanges, a strip, wing bolts extending through the vehicle side boards, through the said metallic guide plates and threadedly engaging said strip, said strip forming a guide during the insertion of the said end gate, said strip wedgedly engaging the said end gate plate

and one of the said guide plate flanges and adapted to engage the end gate plate lips to thereby hold the said end gate in rigid position and to hold the said vehicle side boards in spaced relation.

3. The combination with a vehicle body with side boards, of an end gate with plates rigidly secured to the ends thereof, said metallic plates provided with outstanding lips, guide plates rigidly secured to the body side boards and provided with inwardly extending side flanges, strips fitting between the end gate plates contacting with the outstanding lips thereof and contacting with the outstanding flanges of the body side board plates, and means engaging the body side boards and the said strips, arranged to force the said strips into wedged engagement with the said lips and flanges, to hold the end gate in rigid position.

In testimony that I claim the foregoing as my own, I have hereto affixed my signature in the presence of two witnesses.

LEMMET L. AMSPACKER.
